UNITED STATES PATENT OFFICE.

CHARLES W. FOWELL, JR., OF VIROQUA, WISCONSIN.

MIXING DEVICE.

Application filed April 30, 1925. Serial No. 26,983.

The present invention appertains to new and useful improvements in mixing devices for internal combustion engines, and the primary object of the invention is the provision of means for supplying moisture or moistened air to the explosive mixture as it passes from the carburetor to the intake manifold of the internal combustion engine.

Another very important object of the invention is the provision of a device of this nature which will not only supply moisture to the carbureted gas as it comes from the carburetor, but will also thoroughly mix the carbureted gas and moisten the air before it enters the manifold.

Another very important object of the invention is to provide an attachment of this nature which will introduce moist air into the carbureted gas for thus increasing the combustibility of the fuel mixture and accordingly increasing the efficiency of the engine while tending to cool the engine cylinders, as well as deter the formation of carbon in the firing chambers of the cylinders.

Another important object of the invention is to provide an attachment of this nature which is adaptable for use in connection with the various makes of engines as now upon the market.

Another important object of the invention is to provide an attachment of this nature which may be incorporated in the assembly of the engine without the necessity of providing any holes in the radiator, or other alterations which, through the vibration of the engine would tend to cause leaks in time.

A still further very important object of the invention is to provide an attachment of this nature which is exceedingly simple in its construction, efficient and reliable in use, inexpensive to manufacture and install, not liable to readily get out of order, and otherwise well adapted to the purpose for which it is designed.

Another specific object of the invention is to provide a valve in an attachment of this nature so that the amount of the moistened air may be controlled as may be desired.

With the above and numerous other and incidental objects in view, the invention resides in certain novel features of construction, and in the combination and arrangement of parts as will be hereinafter more fully described and claimed.

In the drawing:—
Figure 1 is a side elevation of an internal

combustion engine and radiator with my improved attachment associated therewith.

Figure 2 is a sectional view through the body portion, and

Figure 3 is another sectional view thereof taken at right angles to that shown in Figure 2.

Referring to the drawing in detail, it will be seen that A designates generally my improved mixing device which is constructed as an independent and detachable unit adapted to be interposed between the carburetor and the intake manifold as is shown in Figure 1. The body portion 10 of the mixing device is preferably formed of metal or other suitable material and is preferably either elliptical or rhombic shaped in plan view to correspond in general outline to the outline of the flanges 11 and 12 of the carburetor 13 and intake manifold 14 respectively, between which it is to be connected. For this purpose, it is provided adjacent its ends with bolt receiving bores 15 through which bolts 16 may be applied to secure it in place. This body member is provided centrally with a gas opening or passage 17 substantially equal in diameter to the internal diameter of the outlet passage of the carburetor and the intake passage of the manifold, and so disposed with respect to the bores 15 as to extend in alignment with said passages and in effect form a continuation of them. As is best shown in Figure 3, this passage is somewhat enlarged adjacent one side to provide a stop shoulder 18. An externally threaded nipple 19 extends downwardly from the body A and the passage or bore 20 thereof communicates with the passage 17.

A ring 21 is adapted to be received in the enlarged portion of the passage 17, and to hold a screen or sheet of foraminous material 22 against the shoulder 18 so as to extend across the intermediate portion of the passage. The ring 21 is provided with an outer annular peripheral groove 23 from which extend openings 24 disposed radially of the ring, and extending through the inferior periphery thereof.

A pipe P is mounted in the upper reservoir of the radiator R and extends downwardly through the connection C and pierces the connection and continues as at P' having a valve V on the end thereof which is in turn connected to an elbow coupling E which is engaged with the nipple 19. The mount

ing of the pipe P does not necessitate the boring of any holes in the radiator R, and therefore the vibration of the engine will not loosen the pipe so as to cause leaks as is the case in similar devices with which I am familiar. When the valve V is opened, or partially opened, the moistened air from the reservoir of the radiator R will be sucked through the pipe P—P', through the valve 10 V, through the coupling E, through the nipple 19, through the groove 23 of the ring 21 and through the openings 24 into the passage 17. The carbureted gas will be broken up by the screen 22 so as to be thoroughly 15 mixed with the moist air, and the mixture of the carbureted gas and moist air will be sucked through the intake manifold 14 in the usual manner.

My improved device may be readily attached to any motor vehicle gas engines now in use without any changes, as practically all such engines are provided with the conventional parts described such as the carburetor, the intake manifold, the radiator, 25 and the connection C. By providing means for adding and thoroughly mixing the moistened air with the explosive mixture from the carburetor, I prevent the formation of carbon in the motor, and upon the 30 spark plug, and also increase the life of lubricating oil used in the cylinders and valves. As a result, the motor is smoother running and more powerful than would otherwise be the case. Other advantages will be 35 apparent to those skilled in the art, and it is thought that the construction and operation will be clearly understood without a

more detailed description. The present embodiment of the invention has been disclosed merely by way of example, and it is apparent that numerous changes in the details of construction, and in the combination and arrangement of parts may be resorted to without departing from the spirit or scope of the invention as hereinafter claimed or sacrificing any of its advantages. 40 45

Having thus described the invention, what I claim as new and desire to secure by Letters Patents is:—

1. As a new article of manufacture, a mixing device including a body having a passage therein, and a nipple extending from the body and having a bore communicating radially with the passage, a ring disposed in the passage having an exterior annular groove communicating with the bore of the nipple and a plurality of apertures extending from the groove into the passage. 50

2. As a new article of manufacture, a mixing device including a body having a passage therein, and a nipple extending from the body and having a bore communicating radially with the passage, a ring disposed in the passage having an exterior annular groove communicating with the bore of the 55 nipple and a plurality of apertures extending from the groove into the passage, said passage being enlarged to receive the ring, and form a shoulder, a sheet of foraminous material extending across the passage held 60 in place against the shoulder by the ring. 65 70

In testimony whereof I affix my signature.

CHARLES W. FOWELL, JR.
